(57) **CLAIM**

What is claimed is the ornamental design for a golf tool, as shown and described.

DESCRIPTION

FIG. 1 is a perspective view of a golf tool, showing the new design;

FIG. 2 is a top plan view thereof;

FIG. 3 is a bottom plan view thereof;

FIG. 4 is a right-side elevational view thereof;

FIG. 5 is a left-side elevational view thereof; and,

FIG. 6 is a front elevational view thereof, the rear elevational view being a mirror image thereof.
